UNITED STATES PATENT OFFICE

RICHARD J. BRITTAINE, JR., OF BLOOMFIELD, NEW JERSEY, ASSIGNOR TO GENERAL MOTORS CORPORATION, OF DETROIT, MICHIGAN, A CORPORATION OF DELAWARE

JOURNAL BOX AND FRAME CONNECTION

Application filed December 2, 1929. Serial No. 411,911.

This invention relates to journal box and frame connections and comprises all the features of novelty herein disclosed. An object of the invention is to provide an improved 5 rocking or tilting connection between a journal box and a car frame. Another object is to provide an improved journal box and saddle wherein load is transmitted from one member to the other at axle level to facilitate 10 free rocking of one member with respect to the other and insure alignment between box and axle without overloading the ends of the bearings. Another object is to provide an improved saddle construction.

To these ends and to improve generally and in detail upon devices of this character, the invention also consists in the various matters hereinafter described and claimed, in its broader aspects, the invention is not necessarily limited to the specific construction selected for illustrative purposes in the accompanying drawings in which

Fig. 1 is a longitudinal central section of an axle box and associated parts.

Fig. 2 is a central cross section of Fig. 1 with the tie bar and a portion of the saddle shown in end elevation.

Fig. 3 is a plan view of a quarter of the saddle which is symmetrical about two axes.

Fig. 4 is half end view and half cross section of the saddle.

Fig. 5 is a section on line 5—5 of Fig. 4.

Fig. 6 is a left side view of Fig. 4.

Fig. 7 is half plan view of the saddle, the other half being a section on line 7—7 of Fig. 4 with the saddle tie-bar in place.

Fig. 8 is a side view of a portion of the box.

Fig. 9 is a plan view of one half of the box.

Fig. 10 is a cross sectional view of a portion of the box.

Fig. 11 is an end view of the tie-bar.

Fig. 12 is a left side view of Fig. 11.

Fig. 13 is a central sectional view of Fig. 11.

Fig. 14 is a perspective view of a seat plate.

In Fig. 1, the numeral 10 indicates a shaft or axle carrying a raceway sleeve 12 receiving roller bearings 14 having end rings 16. The rollers run in an outer sleeve 18 contained 50 in the cylindrical bore of a housing, herein

shown as a car axle box 20. A ring or bushing 22 having a locating flange is pressed into an opening at the inner end of the box, the bushing having grease grooves to seal its joint with the axle. The bushing has a wide internal groove 24 to receive oil thrown off from a rib on the axle and direct it through a hole at the bottom. The bushing has a guiding or wear face 26 for the adjacent bearing end ring 16 and has an exterior peripheral relief groove 28 in communication with the adjacent end of the bearing. This construction allows the lubricant propelled by the rollers to run into the relief groove 28 and down through a notch 30 to a cored-out lubricant receptacle 32 at the bottom of the box, without building up a pressure tending to force lubricant along the axle and out of the box. Holes 34 connect the receptacle with the middle portion of the bearing raceways, and lubricant from the receptacle also has access through a notch 36 to the outer end of the bearings. Lubricant is preferably maintained at a level with the lowermost rollers but, if the supply gets low, surging of the box will deliver it to the bearings at three locations.

The outer end of the box is closed by an end cap 38 having a flange 40 bolted against a gasket. A thrust block 42, preferably of bronze cast around headed stud 44, is clamped against spacing washers 46 by a nut 48. A thrust surface on the block opposes the end of the axle and the block has flat side faces 50 fitting between flattened surfaces 52 on the end cap to prevent rotation. The sides of the block also have cut-out portions or cavities 54 for economy of material, the upper cavity also serving as an oil receiver and communicating through a hole 56 with a space above a lubricating wick 58. Drain hole 56 prevents oil accumulating at 54 and leaking out at stud 44. The wick extends from a notch in the thrust block to the bottom of the box, passing through an opening 60 in an extension 62 on the interior of the end cap. The cap has an arcuate extension 64 at the top and sides to guide and locate the adjacent bearing and there is a relief groove 66 at the bore of the box. An arcuate groove 68 is

formed in the cap directly above the thrust surfaces of the axle and the thrust block, whereby lubricant, thrown centrifugally from the end of the axle during rapid rotation, is caught and allowed to drain down a surface 69 to the cavity 54. This lubricant may be that raised by the wick or that raised by the rollers and running down to the end of the axle. Hence an auxiliary supply of lubricant is collected and drains to the thrust surfaces. Excess lubricant on the thrust surfaces can drop down around the extension 62 and through the notch 36 to the lubricant reservoir.

Exteriorly, the opposite sides of the box have projections 70 braced by webs 72. Cavities are formed in each projection by a bottom wall or shelf 74 and end walls 76. A renewable hardened block or seat plate 78 rests on each shelf between the end walls and has its upper supporting surface 80 cylindrically crowned on a long radius, from the ends to the middle, the middle of the crowned surface being preferably arranged on a level with the center of the axle and offset a little inwardly of the center of the bearings. The projections 70 also have spaced upwardly extending ears or lugs 82 with the inner or facing walls 84 thereof vertically crowned or rounded upwardly and outwardly.

Arching over the top of the box and having clearance therewith is a yoke or saddle 86. The saddle has inwardly extending projections 88 at the sides of the box and fitting between the flaring walls 84 of the ears 82. A cavity is formed in each projection by a horizontal wall 90, end walls 92, and a side wall or boss 94. A hardened block or seat plate 96 fits in each cavity and its lower supporting surface is preferably cylindrically crowned and rests on the crowned rocker surface 80. Hence the saddle and box can have a relative rocking or tilting movement longitudinally of the axle within the limits defined by the spaced and rounded ears 82. Engagement of the ears 82 with the projections 88 on the saddle transmits lateral thrust forces and positions the box with respect to the saddle. The engaging rocker surfaces are at axle level so that the load carried by the saddle does not tend to overload the ends of the roller bearings by canting the box in a vertical plane, the box being free at the center line to rock with respect to the saddle to align itself with the axle at all times. Offsetting the center of the rocker surfaces with respect to the center of the bearings further insures against overloading of the bearings at their outer ends where overloading is more apt to occur. There is a slight clearance between the sides of the box and flat inner walls 98 of the saddle to allow some relative twisting around a vertical axis, as at curves in the track. The boss 94 is prefer-

ably crowned or has a little clearance where it confines the seat plate 78 to facilitate this twisting. The saddle is strengthened by internal flanges or webs 100, a cross web 102, arcuate flanges 104 which extend around the box outside of box flanges 105, and by short webs 106 connecting the flanges 100 and 104. The saddle also has outwardly extending reinforcing ribs 108 near the edges.

The saddle has vertical depending legs 110, at opposite sides of the box, and spring seats or cavities formed by horizontal extensions 112, end walls 114, and side walls 116 having a reinforcing rib 118. The walls 116 have spaced internal faces 120 covered by wear plate legs 122 on a wear plate 124 which covers the saddle legs 110, thus providing a guide for pedestals of the car frame (not shown). The wear plate has a horizontal portion 126 fitting a recess 128 in the extension 112 to support a coil spring. Openings 130 drain the spring seats or cavities and the extensions 112 are braced by webs 132.

Each leg of the saddle has spaced inwardly projecting vertical reinforcing flanges 134 which are substantially continuations of the arcuate flanges 104. These flanges project a little further at the bottom where they have a finished edge 135 and are thickened also to provide securing lugs 136 and 138 (Fig. 5) which have flat sided recesses or depressions 140, one lug 136 having the depression at the outer side and the other lug having the depression at the inner side. Each recess is intended to receive the head of a securing bolt which passes through an opening 142 in the lug and through a tie beam which connects the lower ends of the saddle legs, as hereinafter described.

Below the box and having clearance therewith is a tie beam or connecting member 150 herein shown as a collector beam bracket for third rail cars. The connecting member is symmetrical about a vertical plane through the center of the axle and has an upper flange 152 and a lower flange 154 projecting out towards the front of the axle box and connected by a wall 155. The flanges are convexly crowned and are carried by vertical webs 156 joined by vertical cross webs 158, 160 and 162. The rear cross web 162 projects downwardly and its ends extend beyond the body of the connecting member to form securing lugs 164, each having a bolt opening 166. A short locating lug 168 projects horizontally from each lug 164 to overlie the thickened part of one of the securing lugs 138 of the saddle, and a vertical lugs 170 on the cross web 162 has a finished face to engage the finished edge 135 of the adjacent saddle securing lug 138. A bolt 172 (Figs. 1 and 7) passes through the opening 166 of the lugs 164 and through the opening 142 of the saddle lug 138, the head 174 of the bolt entering the notch or recess 140 of the saddle and a nut 176 clamping the lugs to-

gether. Horizontal flanges 178 and vertical flanges 180 project from the tie beam. Short horizontal lugs 182 are arranged to overlie the securing lugs 136 of the saddle, and a vertical lug 184, braced by a web 186, has a finished face to engage the finished edge 135 of the adjacent saddle lug 136. Each vertical flange 180 has a bolt opening 188 for a bolt 190 whose head 192 enters the notch or recess 140 in the saddle lug 136, the bolt passing through the opening 142 and having a clamping nut 194.

I claim:

1. In a device of the character described, a journal box, an axle journalled in the box, the sides of the box having supporting surfaces projecting outwardly near axle level, a saddle extending over the box and having depending legs at opposite sides of the box, the legs having external flanges forming pedestal ways and having supporting surfaces extending inwardly over the supporting surfaces of the box, the supporting surfaces of the box and saddle being relatively crowned longitudinally of the axle, and the crowning being substantially at axle level; substantially as described.

2. In a device of the character described, a journal box, an axle journalled in the box, the sides of the box having supporting surfaces projecting outwardly near axle level, a saddle extending over the box and having depending legs at opposite sides of the box, the legs having external flanges forming pedestal ways and having supporting surfaces extending inwardly over the supporting surfaces of the box, the supporting surfaces of the box and saddle being relatively crowned longitudinally of the axle, the middle of the crown being substantially at axle level and offset inwardly with respect to the middle point of the journalled portion of the axle; substantially as described.

3. In a device of the character described, a journal box, an axle journalled in the box, the sides of the box having supporting surfaces projecting outwardly near axle level, a saddle extending over the box and having depending legs at opposite sides of the box, the legs having supporting surfaces extending inwardly over the supporting surfaces of the box, the sides of the box having spaced ears projecting therefrom, and the saddle having internal projections entering between the ears; substantially as described.

4. In a device of the character described, a journal box, an axle journalled in the box, the sides of the box having supporting surfaces projecting outwardly near axle level, a saddle extending over the box and having depending legs at opposite sides of the box, the legs having supporting surfaces extending inwardly over the supporting surfaces of the box, the sides of the box having spaced ears projecting therefrom, the saddle having internal projec-

tions entering between the ears, and the ears and the projections having their adjacent walls relatively crowned; substantially as described.

5. In a device of the character described, a journal box, an axle journalled in the box, the sides of the box having supporting surfaces projecting outwardly, a saddle extending over the box and having depending legs at opposite sides of the box, the legs having supporting surfaces extending inwardly over the supporting surfaces of the box, the supporting surfaces of the box and saddle being relatively crowned longitudinally of the axle, the box and saddle having projections on one member entering between spaced ears on the other member, and the ears being rounded on their facing walls to allow the box and saddle to have a relative rocking movement on the supporting surfaces; substantially as described.

6. In a device of the character described, a journal box, an axle journalled in the box, the sides of the box having supporting surfaces projecting outwardly, a saddle extending over the box and having depending legs at opposite sides of the box, the legs having supporting surfaces extending inwardly over the supporting surfaces of the box, the supporting surfaces of the box and saddle being relatively crowned longitudinally of the axle, the box having spaced ears near the ends of the supporting surfaces, the saddle legs having internal projections entering between the spaced ears on the box, and the ears being rounded upwardly and outwardly away from the supporting surfaces; substantially as described.

7. In a device of the character described, a journal box, an axle journalled in the box, a saddle extending over the box and having depending legs at opposite sides of the box, the box and saddle having rocking engagement one with the other longitudinally of the axle, one of said members having a pair of spaced ears and the other member having projections entering between the ears, and the adjacent walls of the ears and projections being vertically crowned; substantially as described.

8. In a device of the character described, a journal box, an axle journalled in the box, the sides of the box having horizontal shelves projecting outwardly, lower seat plates resting on the shelves and having upper supporting surfaces arranged substantially at axle level, a saddle extending over the box and having depending legs at opposite sides of the box, the legs having internal projections and outwardly extending frame engaging members, upper seat plates engaging the projections and having lower supporting surfaces resting on the supporting surfaces of the lower seat plates, and the engaging supporting surfaces being relatively crowned; substantially as described.

9. In a device of the character described, a journal box, an axle journalled in the box, the

sides of the box having horizontal shelves projecting outwardly, end walls at the ends of the shelves, seat plates resting on the shelves and confined between the end walls, the seat plates having upper supporting surfaces arranged substantially at axle level, a saddle extending over the box and having depending legs at opposite sides of the box, the legs engaging the outer sides of the seat plates and holding them on the shelves, and the saddle having outwardly extending frame engaging members and internal projections with supporting surfaces resting on the supporting surfaces of the seat plates; substantially as described.

10. In a device of the character described, a journal box, an axle journalled in the box, the sides of the box having horizontal shelves projecting outwardly, end walls at the ends 20 of the shelves, lower seat plates resting on the shelves and confined between the end walls, the seat plates having upper supporting surfaces arranged substantially at axle level, a saddle extending over the box and having depending legs at opposite sides of the box, the legs engaging the outer sides of the seat plates and holding them on the shelves, the saddle legs having outwardly extending frame engaging members and internal projections with cavities, the cavities having each a horizontal wall and end walls, upper seat plates engaging the horizontal wall and fitting between the end walls, and the upper seat plates having a lower supporting surface resting on the upper supporting surface of the lower seat plates; substantially as described.

11. In a device of the character described, a journal box, an axle journalled in the box, the opposite sides of the box having supporting surfaces projecting outwardly near axle level, said surfaces being crowned longitudinally of the box, a saddle extending over the box and having depending legs at opposite sides of the box, and the legs having outwardly extending frame engaging members and supporting surfaces extending inwardly near axle level and supported on the crowned surfaces of the box; substantially as described.

12. In a device of the character described, a journal box, an axle journalled in the box, a saddle extending over the box and having depending legs at opposite sides of the box, the legs having horizontal extensions, and wear plates attached to the saddle legs and having their lower ends bent to engage the extensions; substantially as described.

13. In a device of the character described, a journal box, an axle journalled in the box, a saddle extending over the box and having depending legs at opposite sides of the box, the legs having vertical side walls and horizontal extensions, wear plates having legs 65 engaging the side walls to form pedestal

ways, and the lower ends of the wear plates having bent portions engaging the extensions; substantially as described.

14. In a device of the character described, a journal box, an axle journalled in the box, a saddle extending over the box and having depending legs at opposite sides of the box, the legs having external flanges forming pedestal ways and internal reinforcing flanges, a tie beam extending under the box, and means for connecting the tie beam to the internal flanges; substantially as described.

15. In a device of the character described, a journal box, an axle journalled in the box, a saddle extending over the box and having depending legs at opposite sides of the box, the legs having external horizontal extensions forming spring seats and internal reinforcing flanges, a tie beam extending under the box, and means for connecting the tie beam to the flanges; substantially as described.

16. In a device of the character described, a journal box, an axle journalled in the box, a saddle extending over the box and having depending legs at opposite sides of the box, the saddle legs having side walls forming pedestal ways, the lower ends of the saddle legs having internally projecting securing lugs, a tie beam extending under the box, and bolts securing the tie beam to the lugs; substantially as described.

17. In a device of the character described, a journal box, an axle journalled in the box, a saddle extending over the box and having depending legs at opposite sides of the box, the lower end of each leg having a pair of internal lugs, a tie beam extending under the box, and bolts securing the tie beam to the lugs; substantially as described.

18. In a device of the character described, a journal box, an axle journalled in the box, a saddle extending over the box and having depending legs at opposite sides of the box, the lower ends of the legs having securing lugs with flat sided recesses, a tie beam extending under the box, and bolts securing the tie beam to the securing lugs and having heads entering the recesses; substantially as described.

19. In a device of the character described, a journal box, an axle journalled in the box, a saddle extending over the box and having depending legs at opposite sides of the box, a tie beam extending under the box and having projecting lugs, the lower ends of the saddle legs having securing lugs engaging said projecting lugs, means for clamping the engaging lugs together, and the tie beam having locating lugs engaging the securing lugs; substantially as described.

In testimony whereof I hereunto affix my signature.
